UNITED STATES PATENT OFFICE.

SAMUEL R. BAILEY, OF AMESBURY, MASSACHUSETTS.

SLEIGH-DASHER SCREEN.

SPECIFICATION forming part of Letters Patent No. 292,275, dated January 22, 1884.

Application filed November 23, 1883. (No model.)

To all whom it may concern:

Be it known that I, SAMUEL R. BAILEY, of Amesbury, in the county of Essex and State of Massachusetts, have invented a new and useful Improvement in Sleigh-Dasher Screens, which will, in connection with the accompanying drawings, be hereinafter fully described, and specifically defined in the appended claim.

This invention relates to the screen which is arranged upon sleigh-dashers at the front part thereof in a vertical plane, for the purpose of arresting the lumps of snow which are thrown backward from the feet of the horse; and the invention consists in combining with the sleigh-dasher a screen composed of glass, either transparent or reflective, secured in a suitable frame adapted to be secured to the sleigh.

In the accompanying drawings, Figure 1 is a perspective view of a sleigh having my improved dasher-screen thereto applied. Fig. 2 is a detached sectional elevation, showing the screen as formed with transparent glass, the end of the frame being shown in elevation, the glass and the upper and lower bars of the frame being shown in vertical transverse section. Fig. 3 is a view like Fig. 2, except that a backing of felt and a wood panel are shown behind the glass, which are used when the latter is reflective, and a section of the runner and dasher are shown, as also the means of securing the screen in position upon the sleigh. Fig. 4 is also a view like Fig. 2, except that the frame is shown as formed of metal, instead of wood, as in the former figures.

Heretofore screens formed of woven wire secured in a frame of metal have been arranged upon sleigh-dashers. These screens are ornamented by being plated with incorrodible metal—such as nickel, silver, or gold—and they are not only very costly, but are also unduly heavy, especially in view of the position they occupy and the necessarily limited strength of the parts upon which they are supported. To provide a screen that will be light, ornamental, cheap, and durable, and that will neither tarnish or corrode, I have conceived the idea of employing plate-glass, secured in a suitable frame adapted to be secured to the dasher, as such screen.

In said drawings, *a a* indicate the sleigh-runners at the forward part, where they are bent to the required curve of the dasher, the dasher proper being shown at *b*. The runners, at the front edge of the dasher, are united by *55* bar *c*, the dasher being seated and secured in a rabbet formed coincidently in said bar and runners, as indicated in Fig. 3, and the runners being further strengthened by iron *d*. When the frame of my screen is formed of *60* wood, I employ two bars, *e*, of a length equal to the width of the dasher, and these are united by cross-bars *f* at each end; and if the glass is to be in two panels, which I much prefer, a center bar, *g*, is also employed. These *65* bars are respectively formed with grooves centrally arranged in their inner faces, to receive the panel of glass shown at *h*, and also the felt backing *i* and wood panel *j*, when these are employed, the several parts being *70* assembled in place, and the bars secured together by glue at the several intersections. This frame is secured to dash-rail *c* by screws *k*, passing up through said bar *c* and threaded in lower bar, *e*, as shown Fig. 3; and the frame *75* is further supported and braced by small metal stays *l*, which are attached to it and to runners *a*, as shown in Fig. 1. Instead of forming the frame of wood, it may be formed of metal longitudinally folded to form a groove *80* to receive the glass, as shown in Fig. 4, and if the packing *i* and wood panel *j* are employed, the metal is so folded as to give the required width of groove in the frame. When the frame is thus formed of metal, it may be in one *85* entire piece, bent at the corners, with curves of small radius, the abutting ends being united in any of the well-known methods; or the frame may be formed of the several pieces employed in the wood frame, the intersecting *90* angles being secured by ornamental re-enforce figures, or in any of the various methods known to metal-workers; but I prefer a wood frame, as being cheaper, neater, and lighter, such wooden frame being preferably formed of *95* rosewood, cherry, or other ornamental wood varnished or polished, instead of being painted.

When it is desired to have the panels of the screen reflective instead of transparent, the panels *h* are of glass that has been silvered or *100*

otherwise rendered mirror-like, the silvering being protected by packing *i* and panel *j*, as shown.

I do not claim, broadly, or in the abstract, 5 the screen described, as I am aware that glass, in great variety of sizes and either transparent or reflective, has been secured in frames of wood or metal either with or without a protective backing, my claim to a patent being 10 based upon the novelty and high degree of utility of the combination of a glass screen with a sleigh-dasher; hence

I claim as my invention—
The combination, with a sleigh, of a screen 15 formed of thick glass, either transparent or reflective, mounted in a supporting-frame, and secured upon the dasher, substantially as specified.
